UNITED STATES PATENT OFFICE.

FRANK W. SANFORD, OF SCHENECTADY, NEW YORK, ASSIGNOR TO GENERAL ELECTRIC COMPANY, A CORPORATION OF NEW YORK.

SNAP-SWITCH.

No. 863,807.

Specification of Letters Patent.

Patented Aug. 20, 1907.

Application filed February 1, 1905, Serial No. 243,627.

To all whom it may concern.

Be it known that I, FRANK W. SANFORD, a citizen of the United States, residing at Schenectady, county of Schenectady, State of New York, have invented certain new and useful Improvements in Snap-Switches, of which the following is a specification.

The present invention relates to cut-out devices for electrical circuits, and more especially to the type of cut-outs known as snap switches in which the 10 movable circuit opening and closing member is given a quick or snap action upon the application of force to the operating part of the device.

The object of my invention is to provide an inexpensive, strong, compact and highly efficient device 15 of this character consisting of a minimum number of parts so designed and arranged that they may be made from sheet metal punchings and assembled or taken apart without the use of special apparatus.

In carrying out my invention I provide a supporting bracket with stops or projections and a suitable transverse bearing for the reception of the shaft of the switch blades, a latch member fulcrumed on the transverse bearing to operate in conjunction with the stops on the bracket to hold the switch blades in extreme open or closed position, while a spring in engagement therewith is being tensioned by an operating lever fulcrumed upon the transverse bearing and provided with shoulders arranged to overlap the latch plate so that upon moving the operating lever through a given angle relatively to the latch plate, the latter will be disengaged from the stops and together with the switch blades move with a quick action to the opposite extreme position under the recoil of the spring. The operative parts are mounted in the usual manner upon an insulating support having suitable stationary contacts and connections for the conductor wires.

For a more complete understanding of my invention reference may be had to the following detailed description and the accompanying drawing forming a part of this specification, in which

Figure 1 shows in perspective the disassembled operating parts of a snap-switch embodying one form of my invention; Fig. 2 is a vertical longitudinal section of a two-button switch base and plate with the operative parts of my switch shown therein; Fig. 3 is a similar view with the switch mechanism in section; Fig. 4 is a transverse section of the switch mechanism; and Fig. 5 is a perspective view of one 50 of the switch-blades.

The base 1 is of porcelain and has a chamber 2 therein opening from the top side. To the upper edges of the end walls of the base are secured by

screws 3 two attaching lugs 4 whereby the base is adapted to be secured to the wall of a house and to 55 which a face plate 5 is connected by means of screws 6. The lower side of the base is apertured at 7 for the entrance of the conductor wires, and adjacent to these holes are binding posts 8 extending upwardly toward the top of the base, while at their lower ends 60 they are clamped in recesses in the base by screws 9 which extend upwardly through the base and into the stationary contacts 10.

The operative parts are carried by a supporting bracket 11 having an arm 12 secured to the lower inner 65 wall of the base between the pairs of stationary contacts 10 by screws 13 extending upwardly through the lower wall of the base and engaging tapped holes in the bracket. The upright arm 14 has a large central aperture 15, a segmental aperture 16, two side stops or projections 17, and at its upper end a segmental recess 18 with radial stops 19 at each end. The central aperture 15 receives an upset bearing block 20 having two-stepped cylindrical surfaces 21 22, an end flange 23, and a central bore 24 in which the main shaft is journaled. 70 Fulcrumed upon the cylindrical surface 21 are the locking plate 25 and the actuating lever 26. The locking plate 25 has a main central part 27 with a notch 28 in its upper end, and at the lower end of the part 27 are oppositely-extending spring arms 29 bent up circularly about 75 a center above the axis of the shaft and each provided with a shouldered notch 30 near its upper end adapted to engage a corresponding stop or projection 17 on the supporting bracket. The actuating lever 26 is provided at each end with an eye 31 for the reception of a rivet 80 32 carried at the inner end of a push-button 33, and at its upper edge with a transverse finger 34 for engaging the spring, and at the lower edge of the lever 26 is formed a segmental shoulder 35 which underlies the circular spring arms 29 so that when the lever is rocked 85 into extreme position the shoulder will engage the eccentrically-curved arm 29 which is in engagement with its respective stop 17 and force it inwardly out of locking engagement therewith. The shoulder 35 is extended at its central section into a transverse stop 90 finger 36 which projects into the segmental aperture 16 so that as the actuating lever is rocked the finger travels back and forth in the aperture and operates to limit the extent of the rocking movement of the lever by contacting with the end walls of the aperture.

The spring 37 is in the form of a helix with its ends 38 39 bent out radially so that when in position they will cross each other and engage opposite sides of the transverse finger 34 of the actuating lever.

The shaft 40 consists of a cylindrical bar with peripheral grooves 41 near each end and two side slots 42 at

some distance from one end for the reception of a slotted crank plate 43 by which the switch-blades and the locking plate 24 are coupled together. The crank plate 43 has an aperture 44 of a size to permit the shaft 40 to be freely inserted, and leading from one side of said aperture across the axis of the plate is a key slot 45 into which the slotted section of the shaft is adapted to be entered and locked against axial and angular movement relatively to the plate. The upper edge of the plate has a long transversely-bent finger 46 which normally overlies the finger 34 on the actuating lever, passes between the ends 38 39 of the spring, through the notch 28 of the locking plate 25, and the segmental slot 18 at the top of the supporting bracket. The crank plate 15 has a second aperture 47 opposite the aperture 44 for the reception of a pin 48 carried by the hub of the right-hand switch-blade 49 whereby the crank plate is held from radial movement on the shaft and the switch-blade is locked in angular relation to the plate.

20 The left-hand switch-blade 50 is similar to the right-hand except that one of the hub plates 51 is provided with a peripheral recess 55 for the reception of the free end of the finger 46 of the crank plate. The switch-blades 49 and 50 are held upon the shaft 40 by split washers 52 sprung into the grooves 41. In order to insure the engagement of the shoulders 30 with the stop projections 17 guides 53 are arranged adjacent the latter which coöperate with cam surfaces 54 on the inner edges of the arms 29.

30 The operation of my device is as follows: Assuming the parts to be in the position shown in Fig. 3 with the left-hand shoulder 30 of the locking plate in engagement with the left-hand stop or projection 17, then, by pressing down upon the right-hand button 33, the actuating lever 26 is caused to move clockwise and its finger 35 carries the end 39 of the spring 37 to the right, while the opposite end 38 is held by the finger 46 of the crank plate 43 which is locked against movement by its engagement with the locking plate 25. As the shoulder 40 35 on the actuating lever 26 approaches the left-hand stop 17 it forces the bent arm 29 inwardly and finally frees the shoulder 30 from engagement with the left-hand stop, whereupon the locking plate 25 is released and moves clockwise under the recoil of the spring 37 45 carrying the switch-blades 49 and 50 and crank plate 43 into the position shown in Fig. 2 where they are brought to rest by the engagement of the crank plate finger 46 with the right-hand shoulder 19 of the supporting bracket. When it is desired to move the switch-blades 50 into closed position the left-hand button 33 is pressed upon and a corresponding series of operations take place in the opposite direction.

I do not desire to restrict myself to the particular form or arrangement of parts herein shown and described, since it is apparent that they may be changed and modified without departing from my invention.

What I claim as new and desire to secure by Letters Patent of the United States, is,

1. In a snap-switch, the combination with a pivoted switch-blade, of a locking member connected to move therewith and having two cam-shaped spring arms adapted to engage a stationary part, a spring acting on said switch-blade, and an actuating lever adapted to tension said spring and having a shoulder thereon adapted to engage alternately with said spring arms to disengage them from said stationary part.

2. In a snap-switch, the combination of a stationary support provided with projections, a pivoted switch-blade mounted upon said support, a locking member connected to move with said blade and having oppositely-disposed spring arms adapted to alternately engage said projections, a spring acting on said switch-blade, and an actuating lever having means to tension said spring and means to disengage said arms from said stops.

3. In a snap switch, the combination of a stationary support provided with projections on one side thereof, a pivoted switch blade carried by said support, a flat locking member for said blade adjacent said support and provided with oppositely-disposed flexible arms adapted to alternately engage the projections thereon, and an actuating lever adjacent said locking plate and provided with means for putting said switch blade under tension and thereafter releasing said locking member from said projections.

4. In a snap-switch, the combination of a stationary support having projections thereon, a bearing block carried by said support, a shaft journaled in said block, a switch-blade mounted on said shaft, a locking plate fulcrumed on said bearing block and provided with oppositely-disposed spring arms adapted to engage said projections, a spring surrounding said bearing block and operatively engaging said switch blade, and an actuating lever fulcrumed on said bearing block adjacent said locking plate and adapted to tension said spring and thereafter disengage one of said spring arms from its respective projection.

5. In a snap-switch, the combination of a supporting bracket provided on one surface with stops and guides, a switch-blade pivotally mounted thereon, a pivoted locking plate for said blade having oppositely-disposed spring arms provided on their inner edges with cam surfaces to engage said guides and on their outer edges with shouldered notches to engage said stops, a spring in operative engagement with the switch-blade, and an actuating lever pivoted adjacent said locking plate and provided with a finger to engage said spring and a shoulder arranged to engage said spring arms and force them out of engagement with their respective stops when the lever is oscillated.

In witness whereof, I have hereunto set my hand this 30th day of January, 1905.

FRANK W. SANFORD.
